UNITED STATES PATENT OFFICE.

JOHN F. O'CONNOR, OF CHICAGO, ILLINOIS, ASSIGNEE, BY MESNE ASSIGNMENTS, TO
W. H. MINER, INC., A CORPORATION OF DELAWARE.

HAND BRAKE.

Application filed January 5, 1923, Serial No. 610,754. Renewed February 16, 1928.

This invention relates to improvements in hand brakes.

One object of the invention is to provide a simple and efficient hand brake, wherein means is provided for rapidly taking up the slack in the brake chain, and subsequently increasing the ratio of leverage to exert greater forces in the final application of the brakes.

Another and more specific object of the invention is to provide a hand brake, of the vertical staff type, wherein automatically operative means for multiplying the effective ratio of leverage of the brake mechanism, is interposed in the connections between the brake staff and the brake mechanism proper.

In the drawing forming a part of this specification Fig. 1 shows a side elevation of my improved hand brake, parts of the car structure being shown in vertical section. Fig. 2 is a horizontal sectional view taken substantially on the line 2—2 of Fig. 1. And Fig. 3 is a vertical sectional view taken substantially on the line 3—3 of Fig. 1.

In said drawing, 10 indicates the end sill of a car, provided with a depending stirrup 11, rigidly secured thereto.

A vertical brake staff 12 is rotatably mounted in the end sill 10, and has its lower reduced end 13 journaled in the horizontal portion 14 of the stirrup 11. At the upper end the brake staff 12 is provided with the usual hand wheel 15, rigidly secured thereto in any suitable manner. The brake staff 12 is also provided with the usual ratchet member 16, rigidly secured thereto, and co-acting with a locking pawl 17 pivoted on the end sill 10 by a pivot bolt pin 18.

The horizontal portion 14 of the stirrup is provided with a bifurcated extension 19, comprising a pair of inwardly and downwardly extending arms 20, terminating in upwardly inclined ends 21. Each of the arms 20 is cut away at the outer side as indicated at 22 to provide inwardly extending slightly upwardly inclined shoulders 23, in alinement with and forming a continuation of the face of the corresponding inclined end 21.

An angularly bent lever 24, comprising a pair of spaced arms 25, is pivotally mounted at one end by means of a pin 26, on the bifurcated extension 19 of the stirrup, so as to swing in a vertical plane. Each of the

arms 25 comprises a short straight portion 27 and a relatively long portion 28 extending upwardly at an angle thereto. Between the arms 25 are journaled a pair of sheave wheels 29 and 30, the sheave wheel 29 being mounted on a pin 31 extending through the arms 25 near the upper ends thereof, and the sheave wheel 30 being mounted on a pin 32 extending through said arms at a point near the bend thereof. The arms 25 are thus held in spaced relation by the sheave wheels 29 and 30 and by extending on opposite sides of the cut away portion of the bifurcation 19. Said arms are held together by the respective pins 26, 31 and 32 thereby forming in effect, a single lever 24. The sheave wheel 30 has its flanges provided with ratchet teeth 33 for a purpose herein-after described.

A brake chain 34 having one end connected to the brake mechanism proper, passes over the top of the sheave wheel 30, partly around the same, and from the sheave wheel 30 over the sheave wheel 29, to the brake staff 12, to which it is secured by the eye bolt 35, as clearly shown in Fig. 1. As shown in Figs. 1 and 3, the chain 34 is fixedly secured to the sheave wheel 30 by a U-shaped anchor bolt 36, passing through a link of the chain.

A gravity controlled locking pawl 37, which is adapted to co-act with the ratchet teeth of the sheave wheel 30, is pivoted between the arms 20 on the pin 26. The engaging end of the pawl 37 is bifurcated as indicated at 38, and provided with a pair of laterally projecting teeth 39, each of which is adapted to engage with a corresponding set of ratchet teeth of the sheave wheel 30. The opposite end of the pawl 37 is provided with an angularly projecting tail piece 40, extending to one side of the pivot and normally engaging with a stop shoulder 41, formed by a web 42 connecting the arms 20.

In the normal position of the parts, when the brakes are fully released, the lower edges 43 of the arms 20 are adapted to rest upon the shoulders 23, and the lever 24 is thus supported in full line position shown in Fig. 1, and the pawl 37 is held in spaced relation with reference to the ratchet teeth of the sheave wheel 30 by the tail 40 thereof engaging with the shoulder 41.

In the operation of my improved hand

brake, the parts are normally in the position shown in full lines in Fig. 1 with the pawl 37 disengaged from the ratchet teeth of the sheave wheel 30. Upon rotation of the hand wheel 15 in a direction to apply the brakes, the staff 12 will be rotated in a direction to wind the chain 34 thereon, thereby taking up the slack in the brake mechanism and pulling the chain over the sheave wheels 30 and 29. During this operation the lever 24 will remain in its lower position, supported by the shoulder 23, due to the action of gravity. As the operation of winding the chain on the staff continues, the brake shoes will come into contact with the car wheels whereupon a greater amount of tension will be created in the brake mechanism and the lever 24 will be gradually raised until the brakes have been fully set. As the lever 24 is swung upwardly on the pivot 26, the sheave wheel 30 will gradually approach the toothed end of the pawl 37 until the teeth thereof engage with the teeth 39 of the pawl, whereupon rotation of the sheave wheel in a direction corresponding to the movement of the chain during the release of the brakes, will be prevented. After engagement of the pawl 37 with the teeth of the sheave wheel 30, the same will be swung upwardly in unison with the lever, until the lever 24 reaches the position where the brakes are fully set, holding the sheave wheel locked against rotation in said direction. It is, of course, obvious, that when the brake has been set, the pawl 17 and ratchet 16 will lock the brakes in tightened position in a usual and well known manner.

The movement of the lever 24 remains substantially constant regardless of the wear on the brake shoes and other parts of the brake mechanism, due to the fact that no movement of the lever occurs until after the slack in the chain and other parts of the brake mechanism has been taken up. The take-up is at its minimum when the wheels, shoes and other parts of the brake mechanism are new, and gradually increase until renewal of the parts must be made, but this variation in take-up obviously has no effect on the throw of the lever 24 in the final application of the brakes, as the same does not become operable until the slack has been fully taken up and the shoes have been brought snugly against the wheels. The dotted line position of the lever 24 in Fig. 1 of the drawing illustrates the approximate position thereof, when the brakes are fully set.

From the preceding description taken in connection with the drawing, it is evident that there is a differential movement between the opposite ends of the chain and that the leverage ratio is greatly multiplied during the final application of the braking pressure, due to the fact that during the upward

swinging movement of the lever 24 toward the brake staff 12, the sheave 29 will approach the staff at a greater rate of speed than the sheave 30, thereby causing a slower pull on that portion of the chain extending from the brake mechanism proper to the sheave wheel 30, than on the portion of the chain extending from the sheave wheel 29 to the brake staff.

Upon release of the brakes, the pull on that portion of the chain 34 extending from the brake-mechanism proper, to the sheave wheel 30 will first cause a swinging movement of the lever 24, away from the staff 12, until the center of mass of the lever is displaced a sufficient distance whereupon the force of gravity will also act to return the lever to normal position. The initiating movement of the lever away from the staff is assured by the locking engagement of the pawl 37 with the teeth 39 of the sheave 30, thereby preventing rotation of the sheave wheel until the lever 24 has approximately reached its lowermost position, whereupon the pawl is disengaged from the teeth of the sheave wheel by being arrested in its movement away from the staff 12, by the tail piece thereof contacting with the stop shoulder 41. The anchoring of the chain to the sheave wheel 30 prevents slippage of the chain over the sheave wheel while the pawl 37 is in locking engagement therewith and thereby positively assures the movement of the lever 24 away from the staff 12 at the beginning of the releasing of the brakes.

I have herein shown and described what I now consider a preferred manner of carrying out my invention, but the same is merely illustrative and I contemplate all changes and modifications that come within the scope of claims appended hereto.

I claim:

1. In a hand brake, including a brake chain, the combination with a vertical brake staff; of a lever pivotally mounted between said staff and the brake mechanism proper and chain guiding means on said lever, said chain guiding means comprising a pair of radially spaced sheaves, said chain connected at its ends to said staff and brake mechanism and passing over said sheaves.

2. In a hand brake mechanism, the combination with a chain winding means; of a lever pivoted at one end; a sheave wheel rotatably mounted at the free end of said lever; a second sheave wheel rotatably mounted, between the ends of said lever; a chain secured to said second named sheave wheel, passing around said first named sheave wheel and having its opposite ends connected to the brake mechanism proper, and said chain winding means respectively.

3. In a hand brake, the combination with chain winding means; of a lever pivoted to a fixed support at one end, said lever being

adapted to swing to normal position under the influence of gravity; a sheave wheel mounted at the free end of said lever; a second sheave wheel mounted between the ends of said lever; a brake chain passed successively around said sheave wheels, said chain having one end secured to the winding means and the other end secured to the brake mechanism proper; and a stop for holding the lever in normal release position.

4. In a hand brake, the combination with a chain winding means; of a lever pivoted at one end; a plurality of guide rolls rotatably mounted on said lever, one of said rolls being located near the pivot point of the lever; a locking dog for positively preventing rotation of said last named roll in one direction; and a chain extending about said rolls, and from one roll to the other, said chain having one end secured to said chain winding means and the other end connected to the brake mechanism proper.

5. In a hand brake, the combination with a chain winding means; of a lever pivoted at one end; chain guiding means on the free end, and between the free end and the pivoted end of said lever, said guiding means comprising a plurality of rotatably mounted rolls; a brake chain extending about said rolls, and from one roll to the other, said chain having one end connected to the chain winding means and the other end connected to the brake mechanism proper.

6. In a hand brake, the combination with a chain winding means; of a fixed support; a lever pivoted at one end to said support; guiding rolls rotatably mounted on said lever, said rolls being located at different distances from the pivoted end of said lever; a locking dog pivoted on said fixed support and co-acting with the roll nearest the pivoted end of the lever to lock said roll against movement in one direction; means coacting with said dog for holding the same disengaged from said roll when the brakes are released; a chain extending about said rolls and from one roll to the other, said chain having one end connected to the chain winding means, and the other end connected to the brake mechanism proper, whereby upon operation of said winding means, a quick take-up of the chain is first effected and the lever is thereafter swung about its pivot, thereby increasing the effective ratio of leverage of said means and bringing the roll nearest the pivot of the lever in engagement with said locking dog.

7. In a hand brake for railway cars, the combination with a chain winding means; of a pair of chain guides, means for holding said guides a fixed distance apart and supporting the same for simultaneous movement towards and away from said winding means, one of said guides having greater movement than the other; and a chain hav-

ing one end connected to said winding means, said chain extending about said guides and from one guide to the other and having its other end secured to the brake mechanism proper, whereby upon operation of said winding means to wind the chain, the chain is first drawn over said guides to take up the slack, and upon increased tension being set up in the brake mechanism, the guides are moved toward said winding means thereby increasing the effective ratio of leverage of said means.

8. In a hand brake mechanism for cars, having a brake rigging proper, the combination with a manually operable member; of a lever pivoted to the car structure; a flexible element attached at one of its ends to the brake rigging proper; movable flexible element receiving means mounted on said lever adjacent the pivot thereof and to which said element is attached; and a chain interposed between said manually operable member and said flexible element receiving means on said lever, operative to initially actuate said flexible element receiving means to increase tension on said element and, after a predetermined degree of tension is obtained in said element, to swing the lever bodily.

9. In a hand brake for cars having a brake rigging the combination with a manually operable member; of a lever pivoted to the car structure; a flexible element attached at one end to the brake rigging proper; rotatable means mounted on said lever around which said element is adapted to be wound; a flexible element between said member and the free end of the lever, operative to pull said free end of the lever away from the brake rigging proper; and means operative to arrest rotation of said rotatable means after said lever has been swung a predetermined amount.

10. In a hand brake mechanism for a car, having a brake rigging proper; the combination with a manually operable rotatable member; of a lever pivoted to the car structure; a chain attached at one end to the brake rigging proper; a chain winding sheave rotatably mounted on said lever and to which said chain is attached; a chain attached at one end to said rotatable manually operable member and leading to the free end of the lever and attached to said sheave; said sheave being rotated when the manually operable member is rotated and tension is applied to the second named chain, said second named chain also being adapted to pull the free end of the lever in a direction away from the brake rigging proper.

11. In a hand brake for cars having a brake rigging proper, the combination with a manually operable rotatable member; of a chain fixedly attached at one end to said

member and at its other end to the brake rigging proper; a sheave wheel over which said chain passes; a second sheave wheel over which the chain passes; and a lever on 5 which said sheave wheels are mounted, whereby said second named sheave wheel is adapted to move bodily when the lever swings.

12. In a hand brake for cars having a 10 brake rigging proper, the combination with a manually operable rotatable member; of a chain attached at one end to said member

and at its other end to the brake rigging proper; a sheave wheel over which said chain passes; a second sheave wheel over 15 which the chain passes, and a lever on which both of said sheave wheels are mounted, said sheave wheels being arranged so that said second named sheave wheel is adapted to move bodily when the lever swings. 20

In witness that I claim the foregoing I have hereunto subscribed my name this 2nd day of January 1923.

JOHN F. O'CONNOR.
